Filed Jan. 9, 1962, Ser. No. 68,237

Term of patent 14 years

(Cl. D61—1)

FIG. 1.

FIG. 2.

FIG. 3.

FIG. 4.

FIGURE 1 is a front elevational view of a camera light light embodying my new design;

FIGURE 2 is a side elevational view thereof;

FIGURE 3 is a rear elevational view thereof; and
FIGURE 4 is a top plan view thereof.

The fragmentary, broken-line showing of a camera and light support-bracket in FIG. 1 is for illustrative purposes only.

The essential features of the camera light are shown in full lines.

I claim:

The ornamental design for a camera light, substantially as shown and described.
